UNITED STATES PATENT OFFICE

JAMES DANDO DAVIES, OF MARTINS FERRY, OHIO

BUILDING BRICK

Application filed July 31, 1930. Serial No. 472,077.

This invention relates to certain structural improvements and refinements embodied in building bricks, especially of the clay variety generally used in the construction of domestic homes and analogous buildings.

The purpose of the invention is to provide simple and economical apertured bricks which can be used in conjunction with standard bricks and the apertured bricks so arranged 10 in superposed spaced relationship as to form a vertical conduit in the brick wall construction to accommodate electric wires, pipes, reinforcing parts or the like, or to simply serve as a flue or a ventilating passage. The 15 invention is mainly designed for use with veneer walls.

The specific structural details and relative arrangement and association thereof will become more readily apparent from the 20 following description and drawings.

In the drawings:

Figure 1 is a fragmentary elevational view, showing the especially designed corners forming bricks as developed in accordance with the present invention.

Figure 2 is a top plan view of a pair of associated corner bricks.

Figure 3 is a side elevational view of one of the corner bricks.

Figure 4 is a top plan view thereof.

Figure 5 is a section on the line 5—5 of Figure 3.

Figure 6 is an assembled view, showing certain of the body bricks arranged in staggered or break joint fashion.

Figure 7 is a top plan view of one of the body bricks.

Figure 8 is a view like Figure 2 showing the pair of bricks in reversed form to provide 40 a differently shaped corner.

For the sake of distinction, I have utilized the numeral 9 to designate the corner brick and the numeral 10 to designate the body brick, so it is possible to use the corner bricks in association with the body bricks 45 as is obvious from examining Figure 6. The brick 9 in each instance comprises a body portion 11, of general rectangular configuration, which is here shown as provided adjacent one end with an offset vertical passage 12. At

the top is an angular recess which forms the female portion of the joint. At the bottom is a depending annular flange 14, forming the male portion of the joint. This allows the pair of bricks seen in Figure 2 to be associated in right angular form with the flange 14, projecting into the annular seat 13, thus defining a portion of one of the conduits in the walls construction. It is to be observed that the passage or aperture 12 is slightly offset at one side, thus producing a convex-projecting portion 15, projecting beyond the edge 16 and a rounded portion 17, merging into the edge 18. When using these bricks 9, in the assembly shown in Figures 2 and 8 for example, an especially fashioned corner in the wall construction is thus designed.

The bricks may be disposed to assume the position shown in Figure 8, for forming one shape of corner or in the position shown in Figure 2, forming a different shape of corner.

Incidentally, when assembling the bricks in superposed fashion, a rod or pipe is struck down through the passage formed by the aperture 12 to reinforce this rounded corner construction. It is to be observed in making this kind of a corner it will be unnecessary to chip the bricks excessively in placing them together. A corner of this rounded configuration will be ornamental. It is of course obvious that the passage produced by joining the bricks together in this manner may be left unobstructed for forming a drain passage or to accommodate wires and other accessories used in the building construction trade.

For sake of distinction, the brick 10 embodies, as will be seen an offset round hole 19, an annular seat 20 in the top, and an annular projecting rib 21, on the bottom and here the portion 22 is of segmental form and projects beyond the intermediate portion of the face 23 of the brick. In using these bricks 9 and 10 in the assembly shown in Figure 6, permits them to be employed in brick joint fashion for providing the conduit at a central point of the wall construction.

It is evident that this brick can be used for reinforcing the corners of brick walls by running a rod through the hole from the bottom of the foundation to the top. It may be used 100

in any design or shape, namely round, square, hexagonal or what not.

In using the round bricks, the square end of the abutting brick can be knocked out by 5 the brick layer so as to fit the round end of the conductor brick, for instance a brick having a concave recess in one end thereof having its recessed part placed against the end 15 of the upper brick 9 as shown in Fig. 6, 10 and a similar brick is placed against the rounded end of the lower brick 9 in said figure. Similar bricks are placed between the bricks 9 in Fig. 2 and bricks having straight ends are placed between the bricks 9 of Fig. 8. 15 Incidentally the term "conductor" is used to indicate a brick having an opening therethrough, for forming a passage or conductor hole in the wall construction. In the construction of brick buildings, when the buildings 20 join one another, and there is no room for conductors and the roof would have to be especially constructed in order to drain water to the rear side of the building, with the use of this invention, on a conductor brick, 25 this is eliminated, for the roof can be arranged to slope at any angle or direction desired.

Even though I have shown and described the preferred embodiment of my invention, it 30 is to be understood that various changes in the shape, size and arrangement of parts may be resorted to, without departing from the spirit of the invention or the scope of the appended claim.

35 What is claimed is:

In a building construction, a veneer wall formed of standard bricks and two sets of 40 tying corner bricks, the corner bricks being of the same thickness as a standard brick, one end of each brick of one set being placed between the ends of a pair of bricks of the other set whereby the bricks of each set are spaced apart to receive between them the end bricks of alternate rows of said standard bricks, the 45 bricks of one set extending in a different direction from the bricks of the other set to form a corner, the corner forming ends of the bricks of the two sets being rounded with an edge of each brick merging into the rounded 50 part and each rounded part having an opening passing therethrough with an annular groove in one face of the brick surrounding the opening, and an annular rib on the other face surrounding the opening, the ribs on one set of 55 bricks fitting in the grooves of the other set of bricks to tie the two sets together with the openings in the bricks of the two sets being in alignment to form a continuous passage at the corner of the building.

60 In testimony whereof I affix my signature.
JAMES DANDO DAVIES.
